(57) CLAIM

The ornamental design for a combined cigar and electronic device case, as shown and described.

DESCRIPTION

FIG. 1 is a bottom perspective view of a combined cigar and electronic device case;

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is rear view thereof.

In the drawings, the broken lines show portions of the combined cigar and electronic device case that form no part of the claimed design.
